Attorneys

UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-DETECTING MECHANISM.

Application filed April 17, 1922; Serial No. 553,668.

To all whom it may concern:

Be it known that I, EPPA H. RYON, a citizen of the United States, residing at Waltham, in the county of Middlesex and State of Massachusetts, have invented a new and useful Weft-Detecting Mechanism, of which the following is a specification.

This invention relates to an improvement in weft detecting mechanism of the type shown in my prior Patent No. 1,352,536 issued September 14, 1920.

It is the object of my present invention to improve the construction therein shown to the end that better bearing surfaces may be provided and that accidental separation of the parts, particularly when detached from a loom, may be prevented.

My invention further relates to arrangements and combinations of parts which will be hereinafter described and more particularly pointed out in the appended claims.

A preferred form of my invention is shown in the drawing, in which—

Fig. 1 is a plan view of my improved weft detecting mechanism;

Fig. 2 is a sectional elevation taken along the line 2—2 in Fig. 1; and

Fig. 3 is a sectional plan view.

Referring to the drawing, I have shown a stand 10 in which a box-like casing 11 is slidably mounted. A fixed detector 12 is secured to the rear end of the casing 11 and a movable detector 13 is pivoted at 14 to said casing. Rearward movement of the detector

tors and slide is limited by a rod 15 slidable in said casing and having a hook-shaped rear end 16 engaging the rear side of a lateral projection 17 on the movable detector 13. The front end of the rod 15 is offset to provide a threaded bearing for an adjusting screw 18 which engages the front face of the stand 10 and thus limits rearward movement of the slide and detectors.

The stand 10 is provided with a cap or cover 20 (Fig. 2) in which a spring 21 is supported on a rod 22 threaded in the rear end of the cover 20 and having a shoulder against which a bracket 23 on the slide 11 is firmly seated by the spring 21. The shoulder on the rod 22 thus co-operates with the sliding rod 15 to limit rearward movement of the casing or slide 11.

A second rod 25 is slidable in the casing 11 and at its rearward end engages the for-

ward side of the projection 17 on the movable detector 13. The rod 25 is provided with a substantially U-shaped return bend 26 at its forward end and the rearward end 27 of the return portion is offset inwardly, as shown in Fig. 3.

At its forward end, the rod 25 engages an arm 28 fixed on a shaft 29 mounted in bearings 30 and 31 and connected by an arm 32 to a rod 33 slidably mounted in an upward projection 34 on the stand 10. A spring 35 yieldingly presses the arm 28 against the laterally projecting forward end of the rod 25.

The rod 33 normally projects into the path of the lever 36 movable in a vertical slot in the projection 34. If the detector 13 engages a sufficient supply of weft in the active shuttle, it will be held from swinging movement and will push the rod 25 forward, withdrawing the rod 33 from the path of the lever 36 and thus rendering the filling replenishing mechanism inoperative.

If the weft is substantially exhausted so that it does not engage the end of the movable detector 13, the detector swings on its pivot 14 as the slide or casing 11 moves forward, leaving the rod 33 in the path of the lever 36 and indicating weft exhaustion and the necessity for weft replenishment. For a more complete description of the general construction and operation of this type of weft detecting mechanism, reference is made to my prior patent above noted.

My present invention relates particularly to the construction of the sliding rod 25 with its return bend 26 and its offset end 27. Several important advantages are secured by the use of the sliding rod formed as shown and described. The bearing surface against the yielding arm 28 is several times as great as that shown in my prior patent. The return bend 26 slides in a slot or recess 38 in the casing 11 and prevents angular displacement of the rod. Furthermore, the offset end 27 engages a lug or projection 40 between the parts 25 and 26 and thus prevents accidental separation of the parts which has heretofore been common, particularly during shipment or when the detecting mechanism was removed from the loom. The rod 25 is, of course, sufficiently resilient so that the rod can be yieldingly pulled out from the casing when desired, or the parts

25 and 26 may be separated by inserting a screw driver or similar tool between them where they project beyond the casing.

Having thus described my invention and 5 the advantages thereof, I do not wish to be limited to the details herein disclosed otherwise than as set forth in the claims but what I claim is:—

1. In a loom, weft detecting mechanism 10 comprising a stand, a casing slidable in said stand, fixed and movable weft detectors mounted on said casing and projecting rearwardly therefrom, an adjustable rearward stop for said movable detector, a yieldingly mounted member connected to indicate substantial weft exhaustion, and a rod slidable in said casing, and disposed between said member and said movable detector, said rod having a laterally projecting portion affording an enlarged bearing surface engaging said member and being bent rearwardly beyond said lateral portion and extending within said casing to prevent angular move- 45
